Primary Examiner — Mimosa De(74) *Attorney, Agent, or Firm* — Panitch Schwarze Belisario & Nadel LLP(57) **CLAIM**

The ornamental design for a wicker saucer chair, as shown and described.

DESCRIPTION

FIG. 1 is a front perspective view of a wicker saucer chair of my new design;

FIG. 2 is a front elevation view thereof;

FIG. 3 is a left side elevation view thereof, a right side elevation view thereof being a mirror image;

FIG. 4 is a rear elevation view thereof;

FIG. 5 is a top plan view thereof; and,

FIG. 6 is a bottom plan view thereof.

The broken lines in the figures are for the purpose of showing environmental structure and form no part of the claimed design.

1 Claim, 6 Drawing Sheets# US D755,552 S
